UNITED STATES PATENT OFFICE

2,662,143

PROTECTED SWITCH

Howard W. Eckles, St. Louis, Mo., assignor to The Emerson Electric Manufacturing Company, St. Louis, Mo., a corporation of Missouri

Application February 25, 1950, Serial No. 146,236

1 Claim. (Cl. 200—168)

1

The present invention relates generally to electric switches, and more particularly to a starting switch for electric motors and the like which incorporates contacts protected against fouling from dust or other matter.

There has long been a need in the woodworking power tool art for a starting switch for the motor of such tools that will not become fouled by sawdust and the like. As is well known, a starting switch is open during utilization of the power tool, since its function is fulfilled as the motor reaches a predetermined speed, so, with presently used switches, sawdust and the like settles on the stationary and movable contacts as the power tool is used. Hence, the contacts become fouled and do not pass current, requiring frequent cleaning. Often the contacts are seriously damaged, both electrically and through careless cleaning.

Therefore, an object of the present invention is to provide a novel switch which incorporates protective means for the contacts.

Another object is to provide a novel switch which includes a substantially dustproof cover or housing for the contacts constructed to move with the movable contact including a resilient member maintaining the same substantially sealed.

Another object is to provide a novel switch incorporating protected contacts which is of simplified, inexpensive, sturdy, efficient construction.

Other objects are to provide a novel switch incorporating protected contacts which reduces maintenance to a minimum, which functions repeatedly and indefinitely without fouling, and which otherwise fulfills the long felt need.

The foregoing and other objects and advantages are apparent from the following description taken with the accompanying drawing, in which:

Fig. 1 is a plan view of a starting switch incorporating the teachings of the present invention;

Fig. 2 is a bottom view thereof;

Fig. 3 is a cross-sectional view on substantially the line 3—3 of Fig. 1;

Fig. 4 is an enlarged fragmentary cross-sectional view through the enclosed contacts and supports; and

Fig. 5 is a view similar to Fig. 4, illustrating a modified construction.

Referring to the drawing more particularly by reference numerals, 10 indicates generally a starting switch which incorporates the concepts

5 of the present invention. A mounting base 12 of insulating material supports a stationary contact 14 secured thereto by an integral rivet 16, the rivet 16 also anchoring a stationary contact terminal 18 to the base 12.

10 The base 12 also supports a resilient conductive blade 20 which includes a returned mounting portion 22 anchored by rivets 23 to the base 12, a divided body portion 24, and diverging legs 26 to the free ends of which are secured pads 28. A terminal extension 29 is formed integral with the mounting portion 22. A housing in the form of a flanged cup 30 is secured to the body portion 24 by an interiorly disposed movable contact 32 through an integral rivet 33 so that the movable contact 32 is in opposed relation to the stationary contact 14 and the latter extends into the cup 30, but is in spaced relation to the walls thereof (Fig. 4). A phenol resin flat washer 34 or the 15 like and a metal washer 36, illustrated in the form of a cup, but which may be flat, surround the stationary contact 14 and are biased toward the flange of the cup 30 by a spiral spring 38 which also bears against the base 12. The spring 38 is effective to maintain the washer 34 in substantially sealing relation with the flange of the cup 30 at all times, a one and a half to three ounce spring having been found suitable to insure good closing engagement.

20 A stop member 42 limits breaking or withdrawal movement of the blade 20 through a T-head 44 (Fig. 3). The stop member 42 is anchored to the base 12 by the rivets 23 which extend through a support portion 46, and it extends through the opening between the arms 26 of the blade 20.

25 Two terminal posts 48 and 50 are mounted on the base 12, the former of which has a lead 49 soldered to the terminal 29. A lead 51 connects the terminal post 50 with the terminal 18.

In operation, as is well known, the pads 28 are engaged by a sliding sleeve indicated at 52 by broken lines to close the switch 10 in the starting of the motor with which it is associated.

30 At a predetermined speed of such motor, centrifugal force effects sliding of the sleeve 52 to free the blade 20.

35 It is to be noted that in the closing and opening actions of the contacts 32 and 14, both remain fully protected by the cup 30 and washer 34, the latter being maintained against the former by the spring 38 at all times. Sawdust and other such matter cannot reach the contacts 32 and 14 to foul them. An airtight relation between the washer 34 and the wall of the contact

14 is not necessary for a continuously operating starting switch, as has been demonstrated under sustained operating conditions.

In Fig. 5 is a modified construction which differs from that previously described in the spring elements. A spring washer **54** replaces the spring **38**, as does a flat metal washer **56** the cup washer **36**, the spring washer **54** maintaining the washer **34** in closing relation with the cup **30**. A second flat metal washer **58** is added as support for the spring washer **54**.

Manifestly, there has been provided a starting switch construction which fulfills the objects and advantages sought therefor.

It is to be understood that the foregoing description and the accompanying drawing have been given by way of illustration and example. It is also to be understood that changes in form of the elements, rearrangement of parts, and substitution of equivalent elements, which will be 20 obvious to those skilled in the art, are contemplated as within the scope of the present invention which is limited only by the claim which follows.

What is claimed is:

In an electrodynamic machine, switch construction comprising, in combination, a base, a stationary contact supported thereon, a movable switch blade supported thereon, a movable contact on 25 said switch blade in opposed make and break relation to said stationary contact, a cup member 30

5
10

surrounding said movable contact and supported by said switch blade for movement therewith, said cup member surrounding a portion of said stationary contact including its contact face, a nonconductive washer movably disposed about the stationary contact and engaging the open face of said cup member, a resilient metallic compression member interposed between said washer and said base for biasing the washer continuously against said cup member for movement therewith, and a stop member supported on the base for withstanding the biasing load of said compression member when the contacts are predeterminedly separated and thereby preventing uncapping of the contact faces.

HOWARD W. ECKLES.
